UNITED STATES PATENT OFFICE.

WILLIAM H. FINNEY, OF TRENTON, NEW JERSEY.

TIP-HOLDER FOR BILLIARD-CUES.

1,260,173.

Specification of Letters Patent. Patented Mar. 19, 1918.

Application filed January 12, 1915. Serial No. 1,819.

To all whom it may concern:

Be it known that I, WILLIAM H. FINNEY, a citizen of the United States, residing at Trenton, in the county of Mercer and State 5 of New Jersey, have invented new and useful Improvements in Tip-Holders for Billiard-Cues, of which the following is a specification.

This invention relates to tip holders for 10 billiard cues, and it has for its object to produce a device of this class which will be simple in construction, inexpensive and easily applied.

A further object of the invention is to 15 produce a tip holder with which the tip is intimately connected, said holder being readily applicable to a billiard cue.

A further object of the invention is to 20 produce a tip holder consisting of a cylindrical member with which the tip is intimately connected in such a fashion that when the holder is applied to the end of the cue, the leather tip will abut directly on the wood, thereby producing that resilient action 25 which is so much desired in this class of devices and which is not attainable where various substances are interposed between the tip and the end of the cue.

A further object of the invention is to 30 produce a tip holder which, while retaining the tip with great efficiency will not in any wise tend to injure the tip, but will on the contrary constitute a guard for the same, insuring long life of the tip.

With these and other ends in view which 35 will readily appear as the nature of the invention is better understood, the same consists in the improved construction and novel arrangement and combination of parts 40 which will be hereinafter fully described and particularly pointed out in the claims.

In the accompanying drawing has been 45 illustrated a simple and preferred form of the invention, it being, however, understood that no limitation is necessarily made to the precise structural details therein exhibited, but that changes, alterations and modifications within the scope of the claims may be resorted to when desired.

50 In the drawing,—

Figure 1 is a perspective view of the improved tip holder.

Fig. 2 is a transverse sectional view of the same.

55 Fig. 3 is a transverse sectional view show-

ing the tip holder with the tip attached, the holder being applied to the end of a cue.

Fig. 4 is a top plan view of the tip holder.

Fig. 5 is a transverse sectional view illustrating a modified construction of the holder. 60

Fig. 6 is a transverse sectional view of the modified holder with the tip attached, the holder being applied to the end of a cue.

Fig. 7 is a sectional detail view taken on 65 the line 7—7 in Fig. 5.

Corresponding parts in the several figures are denoted by like characters of reference.

The improved tip holder consists of a cylindrical or approximately cylindrical slightly tapering sleeve or ferrule 15 made 70 of metal, preferably of brass, and having at one end an inturned annular flange 16. Formed integral with said flange and upstruck from the inner edge thereof are a plurality of sharp pointed prongs or barbs 75 17. These barbs, as seen in Figs. 1 to 4, inclusive, may be slightly tilted outwardly with respect to the axis of the sleeve, the tilt or inclination being, however, slight. As seen in Figs. 5 and 6, the prongs or barbs, 80 here designated by 17', are tilted inwardly in the direction of the axis of the sleeve, and said prongs are slightly cupped or dished on their inner faces, as best seen at 18 in Fig. 7.

The sleeve 15 is provided with longitudinal slots 19 that will enable it to yield resiliently when applied to the end of a cue 20, thereby clamping such cue and engaging the same securely.

The tip 21, which is made of leather in the 90 customary manner, is connected with the holder by pressing the prongs or barbs 17 or 17' into the base of the tip, a suitable die or press being utilized for this purpose. In so uniting the holder with the tip, the prongs 95 17 or 17', following the trend of their original inclination, will become still further inclined; that is to say, the prongs 17 being tilted outwardly will become distended, while the prongs 17' being tilted inwardly 100 will become further converged, and said prongs will thus firmly bind and retain the tip in position upon the holder without the use of extraneous fastening means of any kind. The holders with the tips attached 105 may be furnished at a moderate price and will enable the devotees of the game to keep their cues in good order and repair with very slight trouble and expense. It will be observed that the tip 21 used in connection 110

with the improved holder has a perfectly smooth flat bottom face and that the tip is not weakened by grooving, notching, indenting or otherwise mutilating the bottom face thereof, as is sometimes required.

It will be particularly noticed that when the holder is applied to the cue, the leather tip will abut directly on the end of the cue, not even the thickness of the flange 16 being interposed. This is due to the fact that in assembling the tip with the holder by the application of pressure, the flange 16 becomes actually embedded in the base of the tip. Thus when the holder is applied to the cue, the base of the tip will directly engage the end of the cue, as seen in the drawing. In said drawing, however, the thickness of the metal of which the holder is composed has been considerably exaggerated. In actual practice the thickness of the metal hardly exceeds that of a sheet of ordinary writing paper, and the end of the cue will, therefore, be caused to abut on the bottom face of the tip without materially indenting the latter to cause the flange 16 to become embedded therein.

It will be observed that the improved holder is composed of but a single piece of metal, thus insuring simplicity, inexpensiveness and lessening the liability of the parts becoming detached or disassembled. The tip used in connection with the holder is of the ordinary well known construction, and it requires no preparation whatever to enable it to be assembled with the holder. The holder does not in any way deface or injure the appearance of the tip, and the latter being seated with its outer or rim portion upon the flange 16, and said flange being partly embedded in the base, the tip is thereby materially strengthened and reinforced.

Metallic cue tip holders have heretofore been made, the same being constructed of a plurality of parts or members, usually including a sleeve to engage the end of the cue, and a holding member to engage the cue tip, said sleeve and holder being connected together by means sometimes involving the use of additional parts or connecting members. Devices thus constructed are objectionable, mainly because the resiliency

resulting from direct contact of the base of the tip with the end of the cue is interfered with if not entirely destroyed by interposing parts therebetween. Such devices are also objectionable on account of being more or less clumsy, expensive and difficult to adjust. My improved cue tip holder consists of a single integral metallic part, 60 namely, a sleeve of very thin material having a narrow flange with upstruck prongs, the prongs and flange being seated in the base of the cue tip when the parts are assembled, the entire portion of the base of 65 the tip bounded by the flange being in direct contact with the end of the cue when the parts are assembled. The resultant action is wholly analogous to that of a cue having a tip cemented directly on the end 70 thereof, there being no parts interposed between the cue and the tip to interfere with the resiliency of the stroke.

Having thus described the invention, what is claimed as new, is:—

1. A cue tip holder consisting of a metallic sleeve having at one end an inturned flange, said flange being provided at its inner edge with upstruck prongs, in combination with a cue tip in which said flange and prongs are embedded to securely retain the same.

2. A cue tip holder consisting of a metallic sleeve having at one end an inturned narrow annular flange provided at its inner edge with upstruck prongs slightly tilted with respect to the axis of the sleeve, in combination with a leather tip having a flat smooth bottom face, said prongs and flange being embedded in the tip whereby that portion of the base of the tip which is bounded by the annular flange will be disposed in the plane of the under face of said flange; and a cue engaging the sleeve and having its end abutting directly on that portion of the base of the cue tip which is bounded by the annular flange of the sleeve.

In testimony whereof I affix my signature in presence of two witnesses.

WILLIAM H. FINNEY.
